UNITED STATES PATENT OFFICE

GEORGE K. LEWIS, OF CHICAGO, ILLINOIS, ASSIGNOR TO MET-L-WOOD CORPORATION,
OF CHICAGO, ILLINOIS, A CORPORATION OF ILLINOIS.

PANELED-WALL CONSTRUCTION

Application filed October 18, 1928. Serial No. 313,241.

This invention relates to paneled wall constructions.

A general object of the invention is to provide a wall construction for the interior of rooms and compartments, whereby the necessity for the use of plaster is eliminated, and wherein the walls are made up of the plurality of panels, each comprising laminations of plywood and metal, the panels being fabricated in such manner as to conceal the fastening means therefor.

Another object of the invention is to provide a paneled wall of the character indicated, and wherein strips of the laminated material are utilized for the purpose of providing a decorative effect to form the wainscoting for the wall, the fastening means being of such character that the same are concealed when the fabricated structure is in position, thereby presenting an unmarred exposed surface.

A more particular object of the invention is to provide laminated panels or parts thereof, in connection with which fasteners are embodied in such manner that the same may be secured in position by operations upon the surface of the panel which is to be exposed to view, the fasteners when in position being entirely concealed and serving to maintain the panels or parts thereof in fabricated condition.

Other and further objects of the invention will more fully and clearly appear from the description and claims hereinafter following.

In the drawings forming a part of this specification, Figure 1 is a front elevational view of a wall, or wall finish embodying the invention. Figure 2 is a vertical sectional view through the wall structure corresponding substantially to the line 2-2 of Figure 1. Figure 3 is a horizontal sectional view, corresponding substantially to the line 3-3 of Figure 1. Figure 4 is a rear elevational view of a fragment of a panel and of a stud to which the panel is attached. Figure 5 is an enlarged sectional view taken through the base molding strip and corresponding substantially to the line 5-5 of Figure 1. Figure 6 is an enlarged sectional view taken through

the upper molding strip and corresponding substantially to the line 6-6 of Figure 1. Figure 7 is a rear elevational view, on a smaller scale, of the molding strips shown in Figure 5. Figure 8 is a sectional view on an enlarged scale of the small decorative strips forming a part of the wainscoting and corresponding to the line 7-7 of Figure 1. Figure 9 is a horizontal fragmentary sectional view of the securing means utilized for affixing the portions of the panels to the studs of the framework of the wall. And Figure 10 is a horizontal sectional view through the construction shown in Figure 4.

As shown in the drawings, a framework is provided including vertically extending end studs 10 and 11 and intermediate vertical studs 12. Horizontal joists 13 and 14 are provided at the upper and lower ends of the wall structure. A plurality of panels are provided there preferably being three upper panels 15, 16 and 17 and three lower panels 18, 19 and 20, the lower panels being of smaller size. The panels 15 and 17 are cut out as indicated at 21 so as to fit about the window frames 22-22.

Each of the panels thus far referred to is made up of the plurality of laminations of plywood and metals. As best shown in Figure 9 there are provided three layers of plywood, indicated by the reference character 23, and an outer layer of sheet steel indicated at 24, the layers of plywood and sheet steel, preferably being rigidly secured together by gluing, preferably following the method disclosed in Burnett Reissue Patent No. 14,349, dated September 11, 1917. Each of the panels 15 to 20 inclusive is provided along its inner surfaces at intervals with fasteners 25 adapted to be secured to the studs 10, 11 and 12, all of the fasteners 25 being of similar construction. As best shown in Figure 9, each of the fasteners 25 comprises a flat plate 31, which has an opening 32 through which the shank of a nail 33 projects, the head 34 of the nail being accommodated in a small socket in the outermost layer of the plywood. The plate 31 is held in position by means of rivets 35-35 each having a head and a split shank, the split

ends of the shank of said rivets being upset against the inner surface of the exposed metallic sheet 24 of the panel as indicated at 240. Fasteners of this type are provided at 5 intervals along the inner surfaces of the various panels and may be driven into the vertical studs by striking the outer steel surface of the panel in line with the fastener, with a suitable implement, thereby securing 10 the panels in the desired position from outer exposed surface of the wall, enabling the panels to be applied when access cannot be had to the rear side of the wall.

In some cases where access may be had to 15 the rear face of the wall, fasteners of the type shown in Figures 4 and 10 may be utilized. Each of these fasteners is in the form of an angle bracket having a flange 26 adapted to bear against the inner surface of the related panel 260, and a flange 27 adapted to 20 rest against the adjacent side surface of a post 100. The bracket is secured to the panel by means of rivets 28, the heads of which bear upon the flange 26 of the bracket. The 25 shank of each of the rivets 28 is split, and driven into the layers 230 of the plywood in such manner that the split ends of the rivet are upset against the sheet metal layer 240 as indicated at 29 thereby rigidly securing 30 the bracket to the panel, and at the same time concealing the fasteners when viewing the exterior sheet metal surface 240 of the panel. The brackets are secured to the adjacent post 100 by means of nails 30 driven 35 through the flange 27 of the bracket, as best shown in Figures 4 and 10. In the case referred to where access may be had to the rear of the wall joists, all of the panels may 40 be provided with the angular brackets instead of the fasteners first described and secured to the studs at suitable intervals.

In order to provide an ornamental wainscoting effect at the lower portion of the wall as provided by the frame work and panels referred to, a molding strip 36 is utilized. 45 This molding strip is of the same construction as the panels, and is best shown in Figure 5. The molding strip includes a plurality of layers of plywood indicated at 37, 50 with a veneer of sheet steel indicated at 38, the ends of the metal being turned as indicated at 39 so as to cover the exposed edges of the plywood. A plate 40 is accommodated 55 in a suitable socket 41 provided in the inner surface of the plywood, and said plate is secured in position by rivets 42—42 of the same character as the rivets 28 and 35 herefore described, the rivets 42 having their ends upset against the inner surface of the 60 steel plate 38, as best shown in Figure 5. The plate 40 holds in position a securing element in the form of a nail, the head of which indicated at 44, is accommodated in a socket in the plywood in the rear of the plate 40, the 65 shank 45 of the nail extending outwardly

through the plate so as to project from the inner surface of the molding strip. As many of the fasteners 45 may be provided as desired, and the molding is secured in position by driving the fasteners through the panels 70 and into the studs.

The upper molding strip 46 as best shown in Figure 6 comprises a series of layers of plywood indicated at 47 and an outside veneer of sheet steel indicated at 48, the ends of the sheet steel being turned inwardly to lie against the inner surface of the layers 47 of the strip, as indicated at 49. A plate 50 is provided secured in position by rivets 51—51, the outer surface of the plate 50 lying in 80 the same plane as the outer surfaces of the turned portions 49. A securing member in the form of a nail has its head indicated at 52, disposed in a suitable socket behind the plate 50, the shank 53 of the nail projecting outwardly from the inner surface of the strip and being adapted to be driven into the stud in the same manner as the fastener 45.

A panelled effect for the wainscoting, between the molding strips 36 and 46 is provided by a plurality of rectangular formations 54, all of which are similar. Each of the formations 54 comprises a plurality of molding strips 55 of the character best shown in Figure 8. Each of the strips includes a plurality of layers of plywood shown at 56, and an exterior veneer of sheet metal indicated at 57, the ends of the sheet metal being turned over the edges of the plywood as indicated at 58. The securing fastener 59 has its head 60 interposed between the layers of the plywood 56 and the steel sheet 57, the shank of the nail projecting outwardly from the rear of the strip.

The fasteners 59 are driven into position from the outer surface of the strip. The strips 55 are beveled at their ends as indicated at 61 to provide for the abutting relation of the ends of the strips to form rectangular figures.

By the above described arrangement, it will be appreciated that the provision of the panels eliminates the necessity for providing lathing or plastering, and the panels are secured in position in such manner that the exterior surfaces of all of the panels, as well as the exterior surfaces of the molding strips, are unmarred by the presence of fastening devices.

It also will be appreciated that in the case of the fasteners shown in Figures 3 to 7, inclusive, and 9, that the fasteners may be applied to the panels after the panels themselves are fabricated. In the case of the molding strip shown in Figure 8, the fasteners 59 are placed in position prior to the fabrication of the plywood layers and the steel veneer 57.

While I have herein shown and described what I now consider the preferred manner of

carrying out the invention, the same is merely illustrative, and I contemplate all changes and modifications that come within the scope of the claims appended hereto.

5. What I claim is:—

1. A composite member comprising a plurality of laminations including a steel facing layer and backing layer; a securing element bearing on said backing element; a 10 plate clamping the head of said securing element between the plate and backing element; and means for securing the plate in position, said means extending within said backing member and terminating at the rear side of 15 said facing layer.
2. A composite member comprising laminations of fibrous material and steel, the steel forming an exterior lamination; a fastening device arranged at the side of said member 20 opposite the steel lamination; and means for securing said device in position, said means including rivets extending through said device and having end portions extending through said member and upset against the 25 under surface of said steel lamination.
3. A composite member comprising laminations of fibrous material and steel, the steel forming exterior laminations and the fibrous material forming a backing, a headed fastening device extending outwardly from the 30 backing side of said member, and means for securing said device in position, said means including a metal plate bearing against the backing, through which plate said fastening device is entered to bring its head between 35 said plate and the fibrous backing, and devices entered through the metal plate and into the fibrous backing to secure the plate thereto, the exterior steel lamination remaining 40 imperforate.
4. A composite member comprising laminations of fibrous material and steel, the steel forming an exterior lamination and the fibrous material forming a backing, a headed 45 fastening device located behind the fibrous backing, a plate through which said fastening device is entered to bring its head into contact with the surface of said plate, and devices entered through said plate and into 50 the fibrous backing to secure the plate thereto, the exterior steel lamination remaining imperforate.
5. A composite member comprising laminations of fibrous material and steel, the steel forming an exterior lamination and the fibrous material forming a backing, a headed fastening device located behind the fibrous 55 backing, a metal plate through which said fastening device is entered, to bring its head into contact with the surface of said metal plate, and headed rivets entered through said metal plate to bring their heads against the exposed surface thereof, said rivets having 60 end portions extending through said fibrous 65

backing and upset against the under surface of said exterior steel lamination.

In witness that I claim the foregoing I have hereunto subscribed my name this 10th day of October, 1928.

GEORGE K. LEWIS.
